UNITED STATES PATENT OFFICE.

MARION H. KERNER, OF NEW YORK, N. Y.

FOUNTAIN-PEN.

SPECIFICATION forming part of Letters Patent No. 349,721, dated September 28, 1886.

Application filed May 8, 1886. Serial No. 201,530. (No model.)

To all whom it may concern:

Be it known that I, MARION H. KERNER, a citizen of the United States, and a resident of New York, in the county and State of New York, have invented certain new and useful Improvements in Fountain-Pens, of which the following is a specification.

My invention relates to fountain-pens in which an ordinary writing-pen is connected to an ink-reservoir formed to constitute the holder of the pen, and from which the ink is fed to the pen for writing.

The object of my invention is to provide a fountain-pen which will be simple in construction and certain in its action, and which will "feed" or supply the ink to the pen in a regular manner, and prevent the overflowing of the ink from the pen or undue retention of it in the reservoir.

The invention principally consists in the combination, with a "fountain holder," (or ink-reservoir constituting the holder of the pen,) of a pen formed with a longitudinal groove or channel in its top or back, extending from the heel of the pen to or below the upper or rear end of the slit in the nib of the pen, the pen being secured at its heel in the end of the fountain holder, with the end of said groove in connection with the ink-reservoir, or an outlet from it, whereby the ink may be fed directly from the reservoir to the pen through the groove in its top. This groove is formed of the proper width and depth to enable a sufficient quantity of ink to be fed to the point to supply the pen for writing. The pen may preferably be provided with a cover for the groove, of hard rubber, metal, or other material, extending over part or all of the groove in the pen, to prevent any possible overflow of the ink therefrom.

The invention also embraces other features and details of construction, as described and claimed hereinafter.

In the accompanying drawings, Figure 1 is a longitudinal sectional view of a fountain pen-holder with my invention applied, and Fig. 2 is a transverse section of the holder on the line $\times \times$ of Fig. 1. Fig. 3 is a view of the top or back of the pen, the latter being detached from the holder, and Fig. 4 is a cross-sectional view of the pen on the line $\times \times$ of Fig. 3. Fig.

5 is a longitudinal sectional view of a holder in which a cut-off for the ink from the ink-reservoir to the pen is provided, and Fig. 6 is a view of the end of the fountain-holder containing the pen, showing the cover inclosing the pen, this figure illustrating means whereby the cut-off shown in Fig. 5 may be actuated by turning the pen-cover and pen-holding section. Fig. 7 is a cross-sectional view on line $\times \times$ of Fig. 5. Fig. 8 illustrates the pen as applied to an ordinary holder and when intended to be dipped in the ink, this view showing the top of the pen.

Referring to Figs. 1, 2, 3, and 4, A represents the pen, which may be formed of gold or other metal, and be made with its point of any desired stiffness, and its general outline of the desired or usual form. A groove, a , (best understood from Figs. 1 and 4,) is formed in the back or top of the pen by pressing the metal constituting the back downward or in other suitable manner. The groove a extends in length from the heel down to or beyond the upper or rear end of the slit in the point of the pen. It is obvious that the groove a may extend nearer to or end farther from the point of the pen than is shown in the drawings, and it may, if desired, be carried entirely to the point of the pen. I have found that by making the groove extend very nearly to the extreme point, the slit in the nib extending up through its center, a very good action of the pen may be obtained. The groove a may preferably be provided with a cover, c , of hard rubber, metal, or other suitable substance, extending over the groove part or all of the length of the same, and lapping at its edges on the back of the pen adjacent to the groove. This cover may be secured in place by being fastened to the end of the holder where the heel of the pen is secured, or in any other suitable manner. The barrel or reservoir B is provided with a pen-holding section, b , which may be screwed into the end of the barrel, as shown. A plug, D , having a groove, d , extending longitudinally along its top or upper side, is fitted tightly in the section b , sufficient space being left between the plug and section b to admit the heel and part of the body of the pen, as will be understood from Fig. 1. The groove d in the plug D

may be formed to correspond with the shape of the groove *a* in the pen, so that the latter, when inserted in the pen-holding section, may fit tightly within the groove *d*. The end *e* of 5 the plug *D* may be formed slanting from the upper to the lower side of the plug, along which slanting portion the groove *d* continues. By this slant the ink may be readily guided to the channel *a* in the pen, and when 10 the ink is nearly exhausted from the reservoir the small quantity remaining in the lower end of the barrel will, by the pen and holder being held in the proper position for writing, be conveyed down the groove in the slanting portion of the plug to the channel in the 15 top of the plug and to the pen, instead of remaining between the barrel and the end of the plug, as would be the case if the plug were formed at right angles to its length at its 20 inner end. The upper end of the barrel *B* may be conveniently closed by a plug, *F*, over the outer end of which the pen-cover *G* may be placed when the pen is in use.

A rod, *I*, of metal, hard rubber, or other 25 suitable material, may be provided in the interior of the reservoir *B*, extending from the plug *F* (to which it may be fastened) to or within the groove in the pen, as shown, to facilitate or direct the flow of ink to the pen by 30 capillary attraction or tendency of the ink to follow a solid substance.

Referring to Figs. 5, 6, and 7, *k* represents a ring or plug with a section cut out to form the opening or channel *l*, Fig. 7. This ring or 35 plug *k* is tightly inserted within the barrel. The pen-holding section *b* fits tightly, but so as to be turned, within the end of the barrel, and is held in place by friction with the barrel, instead of being screwed to it, as in Fig. 40 1. The inner end of the pen-holding section *b* and plug *D* are formed at right angles to their lengths. The inner end of the section *b* and plug *D* abut against the plug *k*, and by turning the pen-section *b* in the holder so that 45 its groove *d* is in line with the channel *l* in the plug *k* a continuous channel for the ink is provided from the reservoir to the pen through opening *l* and grooves *d* and *a*, whereas by turning the pen-section *b* around in the holder 50 so that the groove *d* is out of line with the opening *l* in the plug *k* the ink is stopped from the channel *d*, and is thus cut off from the pen, which stoppage of the ink may be desirable when the pen is not in use. A pin 55 or projection, *p*, may preferably be attached to or formed upon the pen-section *b* directly over the channel *d*, and by cutting out a notch in the end of the pen-cover *G*, corresponding to the pin or projection *p*, the pen-cover, when 60 in position upon the pen-section, may be keyed to the latter by the pin, as shown in Fig. 6. When, therefore, it is desired to open or close the ink-channel, it may be accomplished by turning the pen-cover (and consequently the 65 pen-holding section) the required distance to open or close the channel. A guiding-mark,

m, may preferably be formed upon the barrel *B* to indicate the position of the opening *l* in the plug *k*; or stops may be provided to limit the movements of the pen-section to open and close the ink-channel, the stops being arranged in any well-known manner. 70

In Fig. 8 the pen is shown as applied to an ordinary holder, *H*, in which case the pen is supplied with ink by dipping it in the ink. 75 In this arrangement the pen is constructed precisely as described in connection with Figs. 1, 3, and 4, with the exception of a hole, *i*, for admitting ink and air to the covered channel a being provided. 80

When the pen is supplied with ink by dipping, my construction admits of a considerable quantity of ink being held in the pen at one time, and the necessary frequency of dipping is therefore lessened, a considerable space 85 for the ink being provided by the covered channel *a*, to which it may be admitted through the opening *i*. The opening *i* may in some cases be desirable in the pen when used with a fountain-holder to admit air to the ink and 90 facilitate its flow, and, if desired, several openings may be formed to admit air or ink, instead of the one shown.

What I claim herein as my invention is—

1. A fountain-pen consisting of a holder, 95 constituting the ink-reservoir, and a pen formed with a longitudinal groove or channel in its top or back, extending from the heel of the pen to or beyond the rear or upper end of the slit in the point, said pen being secured in the end of the holder, with its groove connected with the ink-reservoir, or with an outlet therefrom, whereby the ink may be conveyed from the reservoir to the point of the pen through said groove in the pen, substantially as set forth. 105

2. In a fountain-pen, the combination of a holder, constituting the ink-reservoir, and a pen formed with a longitudinal groove or channel in its top or back, extending from the heel of the pen to or beyond the rear or upper end of the slit in the point, and provided with a cover inclosing the whole or part of said groove, said pen being secured in the end of the holder, with its groove connected with the ink-reservoir, or with an outlet therefrom, substantially as set forth. 110

3. A fountain pen holder or barrel adapted to act as a reservoir for ink, and a pen-holding section connected therewith, in combination with a plug formed with a longitudinal groove in its upper side, and fitted within said pen-holding section, and adapted to hold the pen between it and the pen-holding section, and a pen formed with a longitudinal channel, extending from its heel to or beyond the rear or upper end of the slit in the point, the pen being fitted within said pen-holding section, with its groove within the groove in said plug, substantially as shown and described. 125

4. The combination of the fountain pen.

holder and the pen formed with a longitudinal groove or channel in its top or back connecting with the ink-reservoir in the holder, and provided with an inclosing cover for said

groove, formed with one or more lateral openings to admit air or ink to said groove, substantially as set forth.

5. The combination of the barrel or reservoir B, the plug k, having opening l, the pen-holding section b, provided with plug D, having groove d, (the inner ends of said pen-holding section and plug D abutting against the

10 plug k,) the pin or projection p, and the pen-cover G, having a notch to fit over the pin or projection p, all being arranged substantially 15 as shown and described.

In testimony that I claim the foregoing as my invention I have signed my name, in presence of two witnesses, this 5th day of May, 1886.

MARION H. KERNER.
